UNITED STATES PATENT OFFICE.

CHARLES H. BEELER, OF PHILADELPHIA, PENNSYLVANIA, ASSIGNOR TO THE
MACKELLAR, SMITHS & JORDAN COMPANY, OF SAME PLACE.

DESIGN FOR A FONT OF PRINTING-TYPE.

SPECIFICATION forming part of Design No. 21,141, dated November 3, 1891.

Application filed February 14, 1891. Serial No. 381,501. Term of patent 7 years.

To all whom it may concern:

Be it known that I, CHARLES H. BEELER, a citizen of the United States, and a resident of Philadelphia, Pennsylvania, have invented a
5 Design for Printing-Type, of which the following
is a specification.

My design for a font of printing-type is fully illustrated in the accompanying typographical impression.

10 The type of the font are known as "initial letters," and the special feature of the design is the combination of a hand and a letter, the hand grasping the letter and having the index-finger pointing to the right. The letters,
15 as shown in the present instance, are all upper-case letters, and are intended for initial letters. Grasping each letter is the represen-

tation of a hand, the index-finger pointing to the right and the thumb and second and third fingers clasping one of the bars of the letters. 20 The style of the present type is known as "light face."

I claim—

The design for the font of type, as herein described, and as shown in the accompanying 25 typographical impression.

In testimony whereof I have signed my name to this specification in the presence of two subscribing witnesses.

C. H. BEELER.
